ATTORNEY.

UNITED STATES PATENT OFFICE

CHARLES SHNEIDER AND JOHN ROEDER, OF NEW YORK, N. Y.

SHAVING BRUSH

Application filed May 24, 1930. Serial No. 455,246.

This invention relates to improvements in toilet articles, particularly to a shaving brush, and it is the principal object of our invention to provide a shaving brush combined with a receptacle for soap or paste and equipped with means for gradually pressing a desired quantity of the soap or paste into the bristles allowing a ready working up of a lather by the brush.

10 Another object of our invention is the provision of a shaving brush of simple and comparatively inexpensive construction, yet durable and highly efficient in its operation.

15 A further object of our invention is the provision of a shaving brush equipped with novel and improved means for gradually feeding any desired quantity of soap or paste to the brush, without danger of losing any of the soap or paste.

20 A still further object of our invention is the provision of a shaving brush comprising a removable head and nozzle for allowing a ready replenishing of the paste supply.

25 These and other objects and advantages of our invention will become more fully known as the description thereof proceeds, and will then be specifically defined in the appended claim.

30 In the accompanying drawings, forming a material part of this disclosure:

Fig. 1 is a longitudinal sectional view of a shaving brush constructed according to our invention.

Fig. 2 is a front elevation thereof.

Fig. 3 are side and end elevations respectively of the inner sleeve.

Fig. 4 is a detail view of the feeder screw.

Fig. 5 is an end view of the feeder screw and its operating plate.

Fig. 6 is a detail front and end elevation respectively of the distributing nozzle.

Fig. 7 are side and end elevations respectively of a washer.

Fig. 8 are similar views of another washer.

As illustrated, the device comprises a handle 10 of any suitable material having an end flange 11, and at its opposite end a flange 12 provided with a groove for the reception of the head 13, as indicated at 14 in Figure 1.

The head 13 holds the holder 15 for the bristles 16.

An inner sleeve 17 is set in handle 10 to extend longitudinally therethrough and has an opening 18 in its end allowing the passage of 55 a screw 19 extending through sleeve 17.

The lower end of sleeve 17 is closed by a cap 20 having a median opening 21 and a nozzle 22 formed therewith extending through the bristle holder 15 into the center 60 of the bristles where it ends in an open mouth 23. The end of screw 19 projects from the handle 10 and carries at this place an operating disc 24.

A pressure washer 25 within sleeve 17 has 65 a finger 26 formed therewith adapted to engage a groove 27 extending longitudinally along the inner wall of sleeve 17.

A washer 28 provides a tight closure at the outer end of the sleeve 17. 70

In operation, the head 13 with nozzle 20 are disengaged from the handle and the screw is withdrawn as far as the pressure washer will permit, and the paste is introduced into the sleeve from a tube or the like. 75

If now the head and nozzle are replaced and the screw is gradually screwed into the sleeve, the pressure washer or plate 25 will gradually press the desired quantity of the paste or soap into the nozzle and out of the same into the bristles which can then be worked into a lather in the usual manner. It will be evident that one filling of the sleeve will be sufficient for a considerable time. 80

It will be understood that we have described and shown the preferred form of our device as one example of the many possible ways to practically construct our device, and that we may make such changes in its general arrangement and in the construction of the 90 minor details thereof as come within the scope of the appended claim without departure from the spirit of our invention. 85

Having thus described our invention, what we claim as new and desire to secure by Letters Patent is: 95

A shaving brush comprising a hollow handle, a head removably attached to one end of said handle, a bristle holder, bristles held in said head, a sleeve longitudinally extending 100

through said handle provided with a groove and adapted to receive paste, a feeding screw extending through the handle and sleeve, projecting from said handle, an operating disc on the outer end of said screw, a feeding disc 5 engaging said screw, a finger on said disc guided in the groove of said sleeve, a nozzle formed with said sleeve having its mouth projecting into said brush, and means for providing a tight closure in said sleeve at the point of entrance of said screw.

10 Signed at New York, in the county of New York, and State of New York, this 23rd day of May, A. D. 1930.

15 CHARLES SHNEIDER.
JOHN ROEDER.
